UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

HEAT EXCHANGE DEVICE

Application filed March 25, 1927. Serial No. 178,490.

My invention relates to heat exchange device and has among its other objects the production of apparatus of the kind described which is convenient, compact, durable, efficient and satisfactory for use wherever found applicable.

A particular object of the invention is to provide improved apparatus for cooling compressed gases, or the equivalent.

10 In one embodiment of the invention an improved heat exchange device is interposed between a plurality of compressors in such manner that compressed air is delivered to the heat exchange device from one of the compressors and is then cooled therein before it is delivered to the second compressor which again compresses it. The improved cooling device preferably comprises a plurality of spaced tubes through which the 15 compressed air is passed so that there will be an efficient exchange of heat between the compressed air and a column of air which is advanced around the tubes by a fan, or the equivalent.

20 Another form of the invention comprises substantially the same apparatus as that described in connection with the first-mentioned form of the invention but in addition, also comprises means for cooling the cooling water which is circulated through the cylinder jackets of the compressors.

25 Many other objects and advantages of the construction herein shown will be obvious to those skilled in the art from the disclosure herein given.

To this end my invention consists in the novel construction, arrangement and combination of parts herein shown and described, and more particularly pointed out in the 30 claims.

In the drawings, wherein like reference characters indicate like or corresponding parts:

Fig. 1 is an elevation of apparatus embodying one form of the invention; and

Fig. 2 is a section taken on line 2-2 of Fig. 1.

The reference characters 52 and 53 designate compressors which, in this instance, are of the double acting type and are adapted to

cooperate to compress air at atmospheric pressure to a relatively high pressure, the air being passed through a radiator unit 54 formed of a heat exchange device 55 which also comprises a radiator unit 56. The radiator unit 54 comprises spaced tanks 57 and 58 which communicate with each other through a plurality of tubes 59 and the radiator unit 56 preferably comprises spaced tanks 60 and 61 which communicate with each other through a plurality of spaced tubes 62. The spaced tubes 59 and 62 may be of any suitable construction but are preferably formed from relatively thin sheet metal and are preferably provided with cooling fins or flanges 64 soldered in header plates 66 which are formed with integral flanges 67 soldered in grooves 68 formed in the tanks 57, 58, 60 and 61. The tank 61 is preferably secured by bolts 69, or the equivalent, to a frame member 70 and the tank 62 is preferably secured by bolts 72, or the equivalent, to a frame member 73, the tanks 58 and 60 being preferably secured by bolts 75, or the equivalent, to a frame member 76 disposed intermediate the aforementioned frame members 70 and 73. The frame members 70, 73 and 76 are preferably rigidly secured to each other by means comprising side plates 77 which cooperate with the frame members to form a chamber 78 in which a fan 79 and an electrical motor 80 are positioned, the fan 79 being secured to the shaft of the motor 80. Secured to the frame member 73 is a bracket 81 which carries the motor 80.

The exhaust ports of the compressor 52 communicate with a pipe fitting 83 which is connected by pipes 84 and 85 and an elbow fitting 86 to the tank 60 and the intake openings of the compressor 53 are connected to the tank 61 by a pipe fitting 87, an elbow fitting 88 and a pipe 89, the exhaust ports of the compressor 53 being adapted to discharge the compressed air into a pipe fitting 90 so that it may be delivered to any suitable apparatus.

The compressors 52 and 53 comprise water jackets 92 and 93, respectively. The water jacket 92 is connected to the tank 57 by an elbow fitting 94 and pipes 95 and 96 and the water jacket 93 is connected to the same tank

by a pipe 98, an elbow fitting 99 and a pipe 100. The water jacket 92 is operatively connected to the tank 58 by suitable elbow fittings and pipes which are identified generally by 5 the reference character 105 and the water jacket 93 is connected to the same tank by suitable elbow fittings and pipes which are identified generally by the reference character 104.

10 The operation of the apparatus is substantially as follows: Assuming that the motor 80 has been operatively connected to a source of electrical energy, it is obvious that the fan 79 will rotate and advance a column of air 15 through the space between the tubes 59 and 62. Now, if the compressors 52 and 53 are set in operation, the compressor 52 will take in air at atmospheric pressure and after compressing it, discharge it into the tank 60. This 20 compressed air will then pass through the tubes 62 into the tank 61 and thence through the pipe 89, the elbow fitting 88 and the pipe 87 into the compressor 53 which discharges it at a higher pressure into the pipe fitting 99 25 which is, of course, connected to any suitable apparatus. When the air is first compressed in the compressor 52, its temperature rises and when it passes through the tubes 62 there will be an exchange of heat through the walls 30 of the tubes so that the compressed air will be cooled. This cooled air is then delivered to the compressor 53 which again compresses it and causes a rise in its temperature. However, the compressed air discharged from the 35 compressor 53 will have a relatively low temperature.

Now, if it is assumed that the water jackets 92 and 93 and that the radiator unit 55 together with the pipes which connect the 40 radiator unit with the water jackets are entirely filled with water, it is readily understood that when the compressors 52 and 53 are again in operation, a thermo-syphonic action will be set up which will cause heated water 45 from the water jackets 92 and 93 to flow upward in the tubes 95 and 98 to be delivered into the tank 57. This water will descend through the tubes 59 and be cooled by the 50 column of air advanced by the fan 42. The cooled water is returned to the water jackets by way of the pipe fittings 104 and 105.

It will be noted that the heat exchange device 54 is substantially unitary in construction 55 and that a single or common means is employed to advance a column of air through the space between the tubes 59 and 62.

Having thus described my invention, it is obvious that various immaterial modifications 60 may be made in the same without departing from the spirit of my invention; hence I do not wish to be understood as limiting myself to the exact form, construction, arrangement and combination of parts herein shown and 65 described, or uses mentioned.

What I claim as new and desire to secure by Letters Patent is:

1. A heat exchange device comprising a pair of spaced tanks, a set of spaced tubes connecting said spaced tanks to each other, a second pair of spaced tanks disposed in substantially the same plane as the first-mentioned pair of spaced tanks, a second set of spaced tubes connecting the second pair of spaced tanks to each other, each pair of tanks being 70 formed with intake and discharge openings, and common means for advancing air, through the spaces between said first and second sets of tubes, said means being connected for support with said tanks and tubes. 75

2. A heat exchange device comprising a radiator unit, a second radiator unit disposed in substantially the same plane as the first-mentioned radiator unit, said radiator units being provided with intake and discharge openings whereby fluids may be circulated therethrough, and common means including rotatable means, the axis of rotation thereof being arranged in a plane transverse to the plane of said radiator unit for subjecting said 90 radiator units to a flow of air to effect an exchange of heat between said fluids and said air, said radiator units being mounted substantially as a single unit on one side of said last named means. 95

3. A heat exchange device comprising a radiator unit, a second radiator unit disposed in substantially the same plane as the first-mentioned radiator unit, said radiator units being provided with intake and discharge openings whereby fluids may be circulated therethrough, and a fan located in a plane which is substantially parallel with said last mentioned plane for subjecting said radiator units to a flow of air to effect an exchange of heat between said fluids and said air, said radiator units being mounted substantially as a single unit on one side of said fan. 100

4. In a device of the kind described, the combination of a plurality of radiator units 105 arranged in the same plane, one of said units providing an element of a liquid passage, and the other providing an element of a fluid passage, air advancing means arranged at one side of said units in a plane substantially 110 parallel to the plane of said radiator units and providing means for advancing air through said radiator units, a housing, said radiator units being extended across an opening in said housing, said housing having means communicating with the atmosphere and said housing providing an element of a support 115 for said air advancing means. 120

In testimony whereof, I have hereunto signed my name.

ARTHUR B. MODINE.
